UNITED STATES PATENT OFFICE.

SOLOMON LEVY, OF WARE, MASSACHUSETTS.

SOLE AND HEEL PLATE.

SPECIFICATION forming part of Letters Patent No. 291,611, dated January 8, 1884.

Application filed November 9, 1883. (No model.)

To all whom it may concern:

Be it known that I, SOLOMON LEVY, a citizen of the United States, residing at Ware, in the county of Hampshire and State of Massachusetts, have invented a new and useful Sole and Heel Plate, of which the following is a specification, reference being had to the accompanying drawings.

My invention relates to heel and sole plates, the object being to provide a plate of neat, cheap, and durable construction, and one that shall be of the minimum weight without detracting from its durability.

With these ends in view the invention consists in the improved construction and combinations of parts hereinafter fully described, and pointed out in the claims.

In the drawings, Figure 1 is a perspective view of a shoe with my improvement applied thereto. Fig. 2 is a bottom view of the same. Fig. 3 is a transverse section on the line $x x$ of Fig. 2.

A represents a shoe having my improved plates applied to the heel and sole thereof.

B represents the sole-plate, which is formed of a single piece of metal, and having the longitudinal slots or slits $a a'$. The outer and inner sides of the strips $b b'$, which are formed with a series of convolutions or projecting portions $c c'$, are provided at their ends with lugs d , adapted to be driven in the sole of the shoe to aid in retaining the plate upon the said shoe.

C C represent a series of spuds or creepers, which are formed integral with the plate, and having their ends pointed to thoroughly prevent any slipping of the same when in use.

D represents a series of spuds or nails for securing the plates upon the sole.

E represents the heel-plate, which is of the same construction as the sole-plate already described, excepting that the slots or slits in

the same extend transversely instead of longitudinally.

It will be apparent from the above description that by forming the plates with longitudinal slots, as shown in the drawings, the weight of the plate is greatly diminished, and yet the sole of the shoe is effectively protected from any wear, the convolutions serving to prevent any wear upon the side of the sole, and the lugs d serving to securely retain the plate upon the sole of the shoe.

These plates are designed more particularly for use upon what are termed "base ball shoes," and shoes of this class which are generally used in athletic sports.

Having fully described my invention, what I claim as new, and desire to secure by Letters Patent, is—

1. The herein-described plate for shoes, formed of a single piece of metal having the longitudinal slots $a a'$, projecting portions $c c'$, provided at their ends with lugs d , adapted to enter the sole of the shoe to aid in retaining the plate thereon, and spuds or spurs C C, formed integral with said plate, substantially as set forth.

2. The combination, with a shoe, of a plate adapted to be secured thereto, formed of a single piece of metal having the longitudinal slots $a a'$, projecting portions $c c'$, provided at their ends with lugs d , adapted to enter the sole of the shoe to aid in retaining the plate thereon, and spuds C C, formed integral with said plate, substantially as set forth.

In testimony that I claim the foregoing as my own I have hereto affixed my signature in presence of two witnesses.

SOLOMON LEVY.
